UNITED STATES PATENT OFFICE.

BURT WILBUR, OF SYRACUSE, NEW YORK.

TROLLEY-SWITCH.

1,122,344.

Specification of Letters Patent. Patented Dec. 29, 1914.

Application filed March 17, 1914. Serial No. 825,293.

To all whom it may concern:

Be it known that I, BURT WILBUR, of Syracuse, in the county of Onondaga, in the State of New York, have invented new and useful Improvements in Trolley-Switches, of which the following, taken in connection with the accompanying drawings, is a full, clear, and exact description.

This invention relates to certain improvements in trolley frogs of overhead trolley systems for electric railways involving the use of a plate supported by suitable sustaining wires and separate leads for the trolley wires coacting with a movable switch point for automatically guiding the trolley from the main lead to either of the branch leads and vice versa.

The main object is to make the leads separate from the plate so that they may be easily and quickly removed or replaced when broken or otherwise impaired without displacing or otherwise disturbing the plate or its stay wires.

Another object is to provide separate clamping devices by which each lead and its corresponding trolley wire section may be simultaneously clamped to the plate by a single operation independently of the other leads.

A further object is to construct the leads and their clamping means in such manner that they may be interchanged, one for the other, on the same plate or used on other plates throughout the system, thereby reducing the number of parts which it is necessary to carry from place to place for emergency repairs.

A still further object is to provide more effective and reliable means operated by the trolley wheel on the car for automatically shifting the switch point into registration with either of the branch leads so as to establish a continuous guide for the trolley in passing from either branch lead to the main lead or vice versa.

Another object is to render the joints between the leads and plate, and also between the switch point and plate, substantially water-proof, and, as far as possible, non-corrodible so that those parts may be more easily and quickly removed and replaced when necessary or desirable.

Other objects and uses relating to spe-

cific parts of the frog will be brought out in the following description.

In the drawings Figures 1 and 2 are respectively top plan and an inverted plan of a trolley frog embodying the various features of my invention, showing also portions of the trolley wires operably connected thereto. Fig. 3 is a longitudinal vertical sectional view, partly in elevation, taken on line 3-3, Fig. 1. Figs. 4 and 5 are enlarged longitudinal and transverse sectional views taken respectively on line 4-4 and 5-5, Fig. 1. Fig. 6 is an enlarged horizontal sectional view of the turning connection of one of the trolley-operating arms for operating the switch point and adjacent portion of the main body or plate of the frog. Fig. 7 is an enlarged detail sectional view of the heel of the switch point showing the adjacent ends of the operating rods therefor. Fig. 8 is an enlarged detail sectional view of the free end of the switch point showing the roller bearing and adjacent portion of the plate together with the contiguous end of the adjacent branch lead. Fig. 9 is a top plan of a portion of a modified form of frog in which both of the branch leads diverge at equal angles from the longitudinal center of the plate.

This frog comprises a comparatively thin, flat plate —1— of malleable iron, cast brass or equivalent light, strong and durable metal elongated in the direction of extension of the main branch trolley wires, as —a— and —a'—, and provided with apertured lugs or ears —2— forming convenient attaching means for the adjacent ends of suitable tie or stay-wires —b— by which the plate may be supported independently of the trolley wires so that the latter may be disconnected from or re-attached to the plate without disturbing or altering its position.

Associated with the plate —1— are separate main and branch leads —3—, —4— and —4'— and a switch point —5—, all of which are adapted to be removed or replaced without in any way altering or disturbing the position of the plate —1—, said leads being of similar construction consisting of comparatively narrow elongated arms having one end provided with cylindrical studs or lugs —6— which are passed

from the underside upwardly through openings or bearings —7— in opposite ends of the plate and extend some distance above the same to form portions of clamping devices by which the leads and their corresponding trolley wires are firmly secured to said plate in a manner presently described, the opposite ends of said leads being extended some distance beyond the corresponding ends of the plate and are provided with lengthwise grooves or seats —8— for receiving the adjacent portions of the trolley wires —a— and —a'—.

The outer ends of the arms are provided with lips or flanges —9— at opposite sides of the grooves bent or crimped over upon the trolley wire to firmly lock the same to their corresponding leads so that the trolley wheel will ride easily from the wire to the leads and vice versa.

The studs —6— are slotted diametrically from the top downward to the plane of the upper surface of the plate —1— for receiving and supporting the adjacent portions of the trolley wires —a— and —a'— which are passed therethrough and also serve to receive vertically movable clamping dogs —10— adapted to engage the upper surfaces of the trolley wires, the upper ends of the studs —6— being threaded and engaged by clamping nuts —11— by which the clamping dogs —10— may be firmly pressed against the upper surfaces of the wires and at the same time serve to draw the inner ends of the leads firmly into engagement with the bottom of the plate, thereby locking each lead and its corresponding trolley wire to the plate in a single operation.

The apertures in the plate —1— through which the studs —6— pass are preferably located some distance from the corresponding end edges of the plate, which end edges are disposed at approximately right angles to the lines of extension of the trolley wires —a— and —a'— and corresponding leads —3—, —4— and —4'— and are engaged by shoulders —12— on the leads to hold said leads against turning in their respective bearings on the plate and at the same time permit the branch leads to be interchanged one for the other or used on the corresponding ends of other plates.

The upper side of the heel of the main lead —3— is preferably cut away to form a recess —13— extending from the inner end toward the axis of the corresponding stud —6— forming a flange —14— which underlies a projection —15— on the heel of the switch point —5— to partially support and guide such switch point in its horizontal rocking movement. This switch point is provided with a pivotal stud —16— journaled in a socket —17—, which opens from

the underside of the plate —1—, but is closed at the top by an integral portion of said plate to exclude dust and other foreign matter. It may be stated here that the inner ends of the leads are spaced apart a sufficient distance to receive the switch point 70 between them and to permit its free operation, the pivotal connection between the switch point and plate being located in close proximity to the adjacent end of the main lead —3—. The lower edge of the switch 75 point is disposed in substantially the same horizontal plane as the corresponding lower edges of the leads so as to form a continuation thereof when registered therewith, the free end of the switch point being provided 80 with a roller bearing —18— riding against the underside of the plate —1— to reduce friction and, of course, travels in close proximity to the adjacent ends of the branch leads with which it is adapted to register 85 as it is moved in one direction or the other in a manner presently described. The main trolley wire —a— and branch —a'— are preferably continuous, but the branch wire —a'— is dead-ended upon the plate after 90 passing through its stud —6— and for this purpose its inner end is passed through the apertured loop —19— on said plate and interlocked therewith as shown more clearly 95 in Fig. 4.

Switch-shifting means.—As previously intimated, the heel of the switch point is always in registration with the adjacent end of the main lead —3— and, therefore, any trolley wheel, which usually follows some 100 distance to the rear of the front of the truck of the car would travel along the main lead and naturally take the heel of the switch point and shift said switch point into registration with the branch lead corresponding 105 to the turnout taken by the car. On the other hand, when the car is traveling in the opposite direction or along either branch toward the frog, it becomes necessary to provide some means actuated by the trolley 110 wheel for shifting the switch into registration with the branch corresponding to the line along which the car travels in order to render the operation of the switch entirely automatic and for this purpose, I have associated with each branch lead separate switch-shifting levers or rock arms —20— and —20'— located in close proximity to but at the outer sides of the inner ends of their respective leads, each rock arm having 115 its inner end provided with an upwardly projecting cylindrical stud or spindle —21— journaled in a corresponding socket —22— opening from the underside of the plate and closed at the top by an integral portion of 120 said plate to exclude dust and other foreign matter, the upper end of each stud being provided with an annular groove —23— for

receiving a cotter key or pin —24— in one side of the socket for retaining the rock arm in operative position and permitting its rocking movement. The opposite ends of 5 each rock arm diverge from its corresponding leads while the intermediate portion thereof is sufficiently close to the corresponding side of the lead to allow it to be engaged by the flange of the trolley wheel in traveling along said lead, thereby rocking said arm to transmit horizontal rocking motion to the switch point through the medium of 10 a link —25—, the free end of each rock arm being connected to the heel of the switch point by one of the links —25— as shown 15 more clearly in Figs. 2, 5 and 7. These links, although comparatively small in diameter, constitute thrust rods and are of sufficient stiffness to transmit motion from 20 the rock arms to the switch point without liability of bending, one end of the thrust rods being pivotally connected to apertured lugs —27— on the free ends of the rock arms —20— and —20'— while their opposite ends converge toward the heel of the 25 switch point and are loosely seated in V-shaped sockets —28— in a segment —15—, which is integral with the heel of said switch point and travels in the recess —13— as 30 shown more clearly in Figs. 3 and 7, said rods being held in operative engagement with the sockets —28— by a cross bar —30— shown in Fig. 7. Assuming now that a trolley wheel of a car is traveling along one of 35 the branch leads, as for example —4— toward the frog and that the switch point is in registration with the other branch lead —4—, then, as the flange of the trolley wheel encounters the corresponding rock arm 40 —20'—, it will rock the free end of said arms outwardly about its axis and produces an end thrust upon the corresponding link —25—, which, in turn, acting upon the adjacent side of the segment —15— at the heel 45 of the switch point will automatically shift the free end of such switch point into registration with the branch lead —4— in time for the trolley to take the switch and be guided thereby to the main lead —3—. In 50 a similar manner, the trolley traveling along the other lead —4— will shift the point of registration therewith by its action upon the corresponding rock arm —20— to guide the trolley from such branch lead to the main lead. The object in connecting the free ends 55 of the rock arms —20— and —20'— to points in close proximity to the heel of the switch point is to produce a quick throw of the switch from one to the other of its positions in time to catch the trolley in its travel 60 from the end of the branch lead.

What I claim is:

1. An overhead trolley frog comprising a plate having attaching means for tie wires,

separate trolley leads, trolley wires secured 65 to the leads, and separate devices for clamping the trolley wires and leads to each other and to the plate.

2. An overhead trolley frog comprising a plate having attaching means for tie wires, 70 separate trolley leads removably mounted on the plate, trolley wires in electrical contact with the leads, and separate clamping devices for securing the trolley wires and their corresponding leads to the plate. 75

3. An overhead trolley frog comprising a plate and supporting wires therefor, separate trolley leads having studs passed through openings in the plate, trolley wires engaged with the leads and studs, and separate devices co-operating with the studs for clamping the trolley wires and leads to each other and to the plate. 80

4. An overhead trolley frog comprising a plate and supporting wires therefor, separate trolley leads having threaded studs passed through openings in the plate, trolley wires engaged with the leads and studs, and separate devices including clamping nuts on the studs for clamping the trolley wires 90 and leads to each other and to the plate. 85

5. An overhead trolley frog comprising a plate having journal bearings therein, separate trolley leads journaled in said bearings, and separate devices for clamping the leads 95 to the plate.

6. An overhead trolley frog comprising a plate having attaching means for tie-wires, leads on the underside of the plate, threaded studs secured to the leads and extending 100 through openings in the plate, said studs being provided with transverse openings therethrough, wires on the top of the plate passed through the openings in the studs, clamping blocks in the stud-openings 105 engaging the wires, and nuts engaging the threaded studs and clamping blocks for securing the leads and wires to opposite faces of the plate.

7. An overhead trolley frog comprising a 110 plate having attaching means for tie-wires, separate trolley leads on the underside of the plate, trolley wires for said leads on the top of the plate, and separate clamping devices having portions thereof extending 115 through the plate for securing the leads and their corresponding wires to opposite faces of said plate.

8. In an overhead trolley frog, a plate having attaching means for tie-wires, a 120 switch point pivoted to the underside of the plate, separate studs passed through said plate at opposite ends of the switch point, trolley leads beneath the plate and having corresponding ends secured to their respective studs, trolley wires above the plate engaged with the upper ends of the studs, and switch-operating means including rock-

ing members coacting with the outer sides
of the leads at the free end of the switch
point close to the junction of said leads with
their respective studs and adapted to be
5 operated by a trolley while running along
such leads.

In witness whereof I have hereunto set
my hand this 6th day of March 1914.

BURT WILBUR.
